UNITED STATES PATENT OFFICE

BERNARD A. STERLING, OF CHICAGO, ILLINOIS

HAIR WAVER

Application filed November 2, 1931. Serial No. 572,538.

My invention relates to hair wavers and more particularly to an improved hair waving device which may be used in connection with a heater for producing a permanent wave. In the common use of these waving devices the hair is separated into locks or hanks and each one of these locks of hair is wound around an individual one of these waving devices.

10 The principal object of the present invention is to provide a hair waving device characterized by an improved construction of fastening clip which clamps over each lock of hair at a point adjacent to the scalp and holds 15 all of the strands of the lock gripped together, preparatory to winding the lock around the waving device. Heretofore, a common practice has been to wrap and tie a piece of string around each lock of hair, adjacent to the scalp, to retain all of the strands of this lock 20 in one group for winding on the waving device. Such practice is a laborious and tedious process, which must be repeated with each 25 lock of hair, and requiring the cutting or releasing of the string wrappings after the waving operation; and, moreover, these string wrappings frequently become untied during the waving of the hair.

30 The present invention avoids all such difficulties, and like difficulties characteristic of prior hair waving devices, by providing a simple and efficient clamp on the waving device which can be instantly engaged and disengaged and which securely grips all of the 35 strands of hair. A particular feature of this clamping mechanism is a unique cam arrangement whereby large or small bunches of hair are gripped with equal effectiveness, and 40 whereby the cam arrangement precludes accidental release of the clamping mechanism. Another feature is a permanently connected relation of the parts whereby none of the parts can become disassembled or separated 45 and possibly lost.

Other features and objects of the invention will appear from the following detailed description of a preferred embodiment thereof. In the accompanying drawing illustrating such embodiment:

hair waving device showing the clamp closed over a lock of hair to grip the same therein, and with the lock of hair wound around the waving device;

55 Figure 2 is a fragmentary plan view of the waving device, looking downwardly upon the V-shaped portion of the clamp;

Figure 3 is a side view looking at the side or edge of the clamp, this view also illustrating a helical arrangement of ribs which 60 may be provided on the spindle of the waving device;

Figure 4 is a sectional view taken approximately on the plane of the line 4-4 of Figure 3 and illustrating the clamping means in 65 greater detail; and

Figure 5 is an elevational view showing a modified arrangement of projections on the spindle around which the hair is wound for 70 producing a more pronounced marcel wave effect.

The present device comprises a spindle 8 around which the lock of hair is wound, such lock of hair being indicated at 9. Fixedly 75 secured to one end of the spindle 8 is my improved clamping device, generally indicated at 10. The latter comprises a relatively stationary clamping jaw 11 which has a V-shaped clamping recess 12 therein and also comprises a cooperating clamping member in the form of a swinging link 13 which is 80 adapted to lock the hair in the V-shaped recess 12.

85 Referring to Figure 3, the jaw 12 is made up with two longitudinally spaced side walls or wing portions 11a, between which is defined a slot or channel 14 extending transversely across the entire width of the jaw 11. The clamping link 13 plays in this transverse slot 14. Below said slot the two spaced wall portions 11a are brought together as indicated at 11b, and a reduced end of the spindle or mandrel 8 is extended through aligned holes in the portions 11b and has its end riveted over as indicated at 15, thereby rigidly 90 fastening the jaw member 11 to the spindle 8. The entire jaw member may be constructed of a single stamping, folded together to provide the two side wall portions 11a, 11a; or 95 two separate stampings may be secured to 100

gether to form this construction. The latter embodiment is illustrated, and in such form laterally spaced rivets 16 may be extended through the two stampings to rigidly secure the same together.

The clamping link 13 is of flat bar formation, having its edges rounded to avoid cutting the hair, substantially as illustrated in Figure 3. A pivot eye 13a at the inner end of 10 said link receives a pivot stud 18 passing through the jaw ears at one side of the recess 12. Mounted on the other end of said link is a thumb nut 21. This end of said link has a cylindrical portion 22 secured thereto or 15 formed integral therewith, and this cylindrical portion is spaced outwardly along the length of the link sufficiently far to clear the points 23 of the jaw ears on this side. Said cylindrical portion is externally threaded for 20 cooperating with the internally threaded hub of the thumb nut 21. To prevent the possibility of the thumb nut being accidentally screwed off the outer end of the threaded boss 22, said boss is provided with a reduced 25 extension carrying a washer 24, over the outer face of which said extension is riveted, this washer being engaged by the hub of the thumb nut 21 when the latter has been screwed outwardly to the desired limit of its travel. 30 Likewise, when the clamping link 13 is swung up to releasing position it is desirable that the thumb nut be prevented from being screwed inwardly completely off the threaded boss portion 22, and to prevent this small spurs 35 project from the edges of said link to limit the inward motion of the thumb nut along the threaded boss 22.

The clamping jaw 11 and the thumb nut 21 have cooperating cam surfaces which 40 function to force the link 13 down into firm clamping engagement with the hair as the thumb nut 21 is screwed inwardly to locking position. The cam surface on the clamping jaw 11 is indicated at 27, this cam surface 45 sloping inwardly and downwardly from the extremity 23 of the jaw ear, and being correspondingly formed on both spaced wing portions of the jaw. The co-operating camming surface on the thumb nut 21 is indicated at 50 28, consisting of a rounded surface formed annularly around the inner end of the hub of said thumb nut.

In the operation of the device the thumb nut is screwed outwardly to releasing position 55 and the link 13 is swung upwardly, whereupon the lock of hair is placed in the V-shaped recess 12 with the clamping device engaging the hair near the scalp. The link is then swung down into gripping relation 60 over the lock of hair and the thumb nut 21 is then screwed inwardly to complete the clamping and locking engagement. The co-action of the two cam surfaces 27 and 28 tends to force the link 13 downwardly against 65 the hair with increasing pressure as the

thumb nut is screwed inwardly and the continuous clamping pressure established between the parts effectively holds the thumb nut 21 against the possibility of working outwardly along the threaded portion 22 to 70 a releasing position.

Referring to Figure 3, the bottom of the transverse slot or groove 14 lies below the bottom of the V-shaped recess 12 and hence there is space for the hair to be forced down 75 into this transverse slot, under the lower edge of the link 13, whereby the effectiveness of the gripping action is increased. Irrespective of the bulk of hair engaged in the clamping device the rounded surface 28 of the 80 thumb nut will have co-action with some point along the relatively long cam surface 27 for effectively gripping the hair.

In Figure 1 I have indicated at 31 a winding and combing device which may be rotatably mounted on the spindle 8 for winding the lock of hair on said spindle and simultaneously combing the hair in such winding process. This type of winding and combing device is disclosed in detail in my 90 co-pending application, Serial No. 490,909 and need not be described in detail here.

The spindle 8 may have a substantially smooth cylindrical contour, as is typical of most of these devices. As illustrative of another construction, in Figures 2 and 3 I have shown the spindle, or at least the major portion thereof adjacent to the clamp, as having helically inclined groups of ribs 33, projecting from the spindle. This portion of the 100 spindle from which said ribs project is preferably of smaller diameter than the cylindrical outer end of the spindle on which no ribs are formed. Said ribs are only formed along opposite portions of the spindle, similarly 105 to segmental portions of an interrupted or discontinuous screw extending along the length of the spindle. When using this type of spindle the lock of hair is wound over the ribs 33 in a direction of winding opposite 110 to the pitch direction of the helical ribs 33.

In Figure 5 I have illustrated a modified arrangement of projections on the spindle 8. In such embodiment these projections 35 are preferably in the form of conically tapered 115 studs having their smaller ends anchored in the spindle. These studs are preferably grouped in two rows along diametrically opposite sides of the spindle. The hair is wound back and forth around and between 120 these studs, and the result is a more pronounced marcel wave effect in the finished permanent wave. It will be understood that the usual heating shell is slipped over the spindle of each of the above described embodiments after the hair is wound on said spindle, in accordance with conventional permanent waving methods. The end of the 125 spindle carrying the hair clamping mechanism will preferably be provided with a heat 130

insulating end member, which is not shown as it is well known.

I do not intend to be limited to the precise details shown or described.

5 I claim:—

1. In a device of the class described, a spindle, two cooperating hair clamping members carried by said spindle, a screw threaded member carried by one of said clamping members, and cam means coacting therewith in the clamping of the hair.

2. In a device of the class described, a spindle, two cooperating hair clamping members carried by said spindle, a screw threaded member carried by one of said clamping members, and cam means associated with the other of said clamping members and coacting with said screw threaded member for causing clamping pressure of said clamping members 20 on the hair.

3. In a device of the class described, a spindle, a hair clamping jaw carried by said spindle, a pivotally swinging clamping member adapted to coact with said jaw for clamping the hair, a screw threaded member carried by said pivotally swinging member, and cam means engaged by said screw threaded member.

4. In a device of the class described, a spindle, hair clamping means carried thereby comprising a clamping jaw having a depressed portion to receive the hair, said clamping jaw having an outwardly curved lip, a pivoted link adapted to grip the hair in said depressed portion, and a screw threaded member engaging under said lip for locking said pivoted link in clamping position.

5. In a device of the class described, a spindle, hair clamping means carried thereby comprising a clamping jaw having a depressed portion, a pivoted link adapted to grip the hair in said depressed portion, a screw threaded member carried by said link for locking the link in clamping position, and a cam surface engaged by said screw threaded member for creating clamping pressure in said link.

6. In a device of the class described, a spindle, hair clamping means carried by said spindle comprising a clamping jaw, a cooperating movable clamping member adapted to press the hair against said clamping jaw, and a screw threaded member mounted directly on said movable member for locking the same in clamping position, said jaw and said screw threaded member having cooperating surfaces for pressing the hair downwardly against said jaw upon tightening movement of said member.

60 7. In a device of the class described, a spindle, hair clamping means carried thereby comprising a clamping jaw, a coacting clamping member adapted to press the hair against said jaw, means pivotally supporting one end of said latter member on said

spindle, and screw threaded means carried directly on the other end of said member for locking said member in clamping position, said screw threaded means having camming engagement with said jaw whereby tightening of said means causes said clamping member to move inwardly with respect to said jaw.

8. In a device of the class described, a spindle, hair clamping means mounted on said spindle comprising a clamping jaw having depressions formed therein substantially at right angles to each other, the hair being adapted to be received in one of said depressions, a cooperating clamping member movable into and out of the other of said depressions for engaging the hair in said first named depression, and means for securing said cooperating clamping member in clamping position, said last named means having engagement with said jaw to force said clamping member downwardly into said depressions upon tightening movement thereof.

9. In a device of the class described, a spindle, hair clamping mechanism carried by said spindle comprising a hair clamping jaw, said jaw having a transversely extending slot therein, a cooperating clamping member movably mounted in said slot, means for locking said latter member in hair clamping position, an outwardly curved projecting lip on said jaw, and a cooperating surface on said locking means for urging said clamping member into said slot upon tightening of said locking means.

10. In a device of the class described, a spindle, hair clamping mechanism carried by said spindle comprising a clamping jaw having a V-shaped depression therein, a link pivoted to one side of said jaw and adapted to swing into clamping position transversely across said depression, a thumb nut having threaded mounting on said link, and a cam surface on the other side of said jaw adapted to be engaged by said thumb nut for clamping and locking said link.

11. In a device of the class described, a spindle, hair clamping mechanism carried by said spindle comprising a clamping jaw, a link pivotally connected with one side of said jaw and adapted to be swung into position to clamp the hair between said link and said jaw, a thumb nut having threaded mounting on the swinging end of said link, and a cam surface associated with said jaw and engageable by said thumb nut for causing motion of said link toward said jaw as said thumb nut is screwed against said cam surface.

12. In a device of the class described, a spindle, hair clamping mechanism carried by said spindle comprising a clamping jaw having spaced wing portions defining a transverse slot therebetween, said jaw being formed with a hair clamping depression sub-

stantially at right angles to said transverse slot, a link pivotally mounted at one end between said wings at one side of said jaw and adapted to swing down into said transverse slot for clamping the hair between said link

5 and said depression, a thumb nut having threaded mounting on the swinging end of said link, and a cam surface on the other side of said jaw adapted to be engaged by said thumb nut as the latter is screwed inwardly 10 for causing a downward pressure of said link to grip the hair between said link and said jaw.

13. In a device of the class described, a spindle member, and a plurality of tapered projections carried by said spindle with their larger ends outermost, the hair being wound around and between said projections in forming a wave therein.

14. In a hair waving device, a spindle, 20 clamping means mounted at one end of said spindle and extending normal thereto comprising a clamping jaw, a clamping member having relative pivotal movement with respect to said jaw, and means for locking said member in clamping position, and a winding member having longitudinal movement along said spindle for winding the hair thereabout.

15. In a hair waving device, a spindle, 30 clamping means mounted at one end of said spindle and extending normal thereto comprising a clamping jaw, a clamping member having relative pivotal movement with respect to said jaw, means for locking said member in clamping position, and a winding and combing member having longitudinal movement along said spindle.

16. In a hair waving device, a spindle, 40 said spindle having a portion of reduced diameter provided with projecting integral ears for receiving hair therebetween, clamping means for said hair mounted at one end of said spindle and extending normal thereto comprising a clamping jaw, a clamping member having relative pivotal movement with respect to said jaw, means for locking said member in clamping position, and a winding member having longitudinal movement along said spindle for winding the hair thereabout.

45 17. In a hair waving device, a spindle, said spindle having a portion of reduced diameter provided with helically projecting members for receiving hair therebetween, clamping means mounted at one end of said spindle 55 and extending normal thereto comprising a clamping jaw, a clamping member having relative pivotal movement with respect to said jaw, means for locking said member in clamping position, and a winding member 60 having longitudinal movement along said spindle for winding the hair thereabout.

18. A clamping member adapted to be disposed at one end of a hair waving spindle comprising a pair of clamping jaws secured 65 in abutting engagement, each of said jaws

having outwardly offset portions, a clamping member pivotally secured between said offset portions of said jaws, and means carried upon said member for locking it in clamping position with respect to said jaws.

70 19. A clamping member adapted to be disposed at one end of a hair waving spindle comprising a pair of clamping jaws secured in abutting engagement, each of said jaws having outwardly offset portions, said offset portions having transversely extending depressions formed therein, a clamping member pivotally secured between said offset portions of said jaws and adapted to be moved downwardly into clamping position past said depressions, and means carried upon said clamping member for locking it in clamping position with respect to said jaws.

75 80 In witness whereof, I hereunto subscribe my name this 30th day of October, 1931.

85 BERNARD A. STERLING.
